UNITED STATES PATENT OFFICE

105,068

DESIGN FOR A CLOCK CASE

William Brown Cleland, Toronto, Ontario, Canada, assignor to Joseph E. Seagram & Sons, Limited, a company of Canada

Application May 13, 1937, Serial No. 69,344

Term of patent 14 years

To all whom it may concern:

Be it known that I, William Brown Cleland, a subject of the King of Great Britain, residing at Toronto, in the county of York, Province of Ontario, Canada, have invented a new, original, and ornamental Design for a Clock Case, of which the following is a specification, reference being had to the accompanying drawing, forming part thereof.

On the drawing—

Figure 1 is a side elevational view, and

Figure 2 is a top plan view of a clock case showing my new design.

The clock case presents substantially the same appearance from all four sides.

The numerals shown through the arcuate of the clock case are merely representative.

I claim:—

The ornamental design for a clock case, as shown and described.

W. B. CLELAND.
